UNITED STATES PATENT OFFICE.

JAMES P. SKARTCHSEARIS, OF JAMESTOWN, NEW YORK.

TRACK-SWITCH-TRIPPING MECHANISM.

Application filed May 13, 1921, Serial No. 469,282. Renewed August 14, 1922. Serial No. 581,840.

To all whom it may concern:

Be it known that I, JAMES P. SKARTCHSEARIS, a subject of the King of Greece, residing at Jamestown, in the county of 5 Chautauqua and State of New York, have invented certain new and useful Improvements in Track-Switch-Tripping Mechanism, of which the following is a specification.

10 This invention relates to improvements in trip mechanisms for track switches in general, and more particularly to that type of switch actuating mechanism adapted to be mounted on the front portion of a locomotive, or other similar motor car, such as disclosed in my copending application, Serial Number 469,281, filed May 13, 1921, and in my Patent Number 1,371,987, dated March 15, 1921.

15 The primary object of the invention resides in the construction of a trip mechanism to be carried by and at the front of a train whereby a left or right hand trip may be actuated to open or close a switch 25 to permit the train to pass in its proper direction.

Another and very important object of the invention resides in the provision of a trip operating mechanism of the type above set forth for pneumatically or mechanically actuating a trip bar whereby the left or right hand trip situated outside of the track rails may be operated to open or close the switch.

30 Another and equally important object of the invention resides in the construction of a switch operating mechanism which will be extremely simple, consisting of comparatively few parts therefor inexpensive to manufacture, efficient and positive in operation, practical, capable of being easily installed, and easily operable from a position within the train and embodying the elements of safety requisite to mechanisms of 45 this character.

With these objects in view and others which will be suggested and manifest as the purpose and nature of my invention is revealed in the following specification and 50 drawing,

Figure 1 is a fragmentary elevation showing the improved trip mechanism as applied to the forward end of a locomotive for the operation of a switch.

55 Fig. 2 is a fragmentary plan view showing the slidable trip bar and the pneumatic

means for operating the trip in reversed directions transversely of the locomotive,

Fig. 3 is a fragmentary plan view of one end of the trip bar, partly in section, showing one of the trip rollers carried thereby,

Fig. 4 is a detail view, partly in section, of the roller mounting,

Fig. 5 is a fragmentary front elevation of a locomotive showing a modified form 65 of the invention as applied thereto,

Fig. 6 is a side elevation of one of the guides for the roller trip devices,

Fig. 7 is a vertical section showing the 70 roller supporting members, and,

Fig. 8 is a sectional view taken on the line 8—8 of Fig. 5.

Referring now to the drawings, wherein like characters of reference designate corresponding parts throughout the specification, the numerals 5 and 6 indicate the main track rails, and 7 and 8 the trip levers mounted on supports 9 and 10 secured on the opposite ends of the tie 11, and outside of the main track rails 5 and 6, the 80 trip lever being adapted, when operated by a passing train, to actuate pull rods 12 leading to the switch as disclosed in my copending application hereinbefore referred to.

85 The trip lever operating mechanism, which is mounted on the front portion of the engine 13, consists primarily of a transversely movable bar adapted to be pneumatically operated to the left or right to 90 actuate the trip levers 7 and 8 in the manner to be described in detail.

The trip bar 14, which is provided with rack teeth 15 throughout a portion of its length and intermediate of its ends, is 95 adapted for transverse movement, being supported by angular brackets 16 and guided by a member 17 whereby its true horizontal position may be maintained at all times and thus positively operate the trip 100 levers 7 and 8, as is well understood.

The ends of the bar 14 are purposely provided with integral downwardly extending arms 18 and 19 which support the boxings 20 which receive the spindles 22 of the friction rollers 23 which are removably and resiliently held by the pins and springs 24 and 25, respectively, as clearly shown by Figs. 3 and 4 of the drawings.

110 The rack bar 14 is operable by the rack pinion 26 supported by the spindle 27 rotatably mounted in the bracket and guide

28, 29, the upper terminal of said spindle 27 being connected to an arm 30 operable either by compressed air or steam. The opposite end of the arm 30 is provided with 5 a slot 31 which affords a loose connection with the ends of a piston rod 32 extending within a cylinder 33. The air conduits 34, 35 connected to the opposite ends of the cylinder 33 are controlled by a valve 36 10 located with the cab of the locomotive, whereby the piston rod 32 may actuate the arm 30 and the spindle and rack pinion carried thereby to the left or right and thus operate the bar 14 accordingly. As the 15 respective rollers 23 are moved into engagement with the trip levers 7 and 8, the switch will, of course, be actuated to open or closed position as desired. It will be readily seen that the operation of the trip 20 mechanism is preferably automatic, being controlled by the valve 36 to operate the bar 14 to the left or right with facility and ease.

Referring now to the form of the invention shown in Figs. 5 to 8, inclusive, a modified form of trip mechanism is provided, and the same is operable from a point within the cab of an engine, whereby the trip devices or rock shafts mounted on the track, 25 such as is shown in my patent above identified, may be selectively operated when desired or necessary to effect a change in the position of the points of a track switch.

In this construction, rock shafts 40 are 30 disposed transversely of the track, and are journaled in the webs of the rails, and have bent ends portions or arms 46 extending into the path of the trip devices carried on a locomotive at points outwardly of the rails, 35 and outwardly of guide members associated with each of the rails. The lower flange 47 of each of said guides is secured beneath the base flanges of the rail and have their vertically extending portions 45 terminating 40 in a wide flange 48 angularly disposed outside of and above the top of the adjacent rail, the last mentioned flange being adapted to guide one of a pair of trip rollers to be hereinafter referred to. Suspended from 45 50 and carried by the body 49 of an engine cab (not shown), and equally spaced inwardly from the opposite sides thereof, are tubular members 51 supporting a transverse cross beam 52, which is provided with apertures 53 therein in alignment with the bore of the tubular members 51. A slidable collar 54, in each of the said tubular members 51, is provided with a transverse pin 55 supporting the roll carrying rod 56 which depends 55 60 downwardly of the members 51 and through the apertures 53 of the beam 52, the said rod carrying a pair of rollers 57, 58, at its lower end, which rollers are adapted to be projected downwardly of the cab body, one for engagement with the flange 48 of one of

the roller guides, and the other to strike and actuate the bent arm 46 of the rock shaft.

A pair of links 59 are connected to the opposite ends of the pins 55 extending transversely through the tubular members 51, the 70 said pins 55 being slidably carried by the collars 54 and have their opposite ends projecting outwardly of vertically elongated slots 60 formed diametrically of the said members 51. The rods 56, on the upper end 75 of which the collars 54 are secured by means of the pins 55, are normally sustained upwardly of the tubular members 51 by means of coiled springs 61 being interposed between the collars 54 and the lower end walls 80 of the said members 51. The links 59, above referred to, are pivotally connected, by means of pivot pins 63, through the laterally extending arms 62, which are, in turn, pivotally connected at their inner ends, by means 85 of pivot pins 64 to a stationary bearing 65, said bearing 65 being rigidly secured in position intermediately of the opposite ends of the cross beam 52. Each of the arms 62 are provided with friction rollers 66 supported by pins 67 on raised extensions or 90 bearings 68 at points substantially intermediate the ends of the said bearing arms. An upwardly extended lever 69 is passed through a slot 70, formed in the body 49, 95 and projected into the cab proper of the locomotive, and is provided with a right angled arm 71 which is adapted to be rocked into engagement with the friction roller 66 correspondingly for the depressing of either 100 of the said bearing arms 62, at the right or left hand side of the locomotive, as is shown by dotted lines on Fig. 5.

The lever 69 is provided with a pin 69^a 105 cooperating with the raised projection of a rocking member 70^a, the said lever being adapted to rotate on said rocking member so as to dispose the arm 71 into engagement with the levers 62. The rocking member 70^a 110 is pivotally mounted on the central shaft 72 of the bearing and is provided with a detent 73 and spring 74 which ride over a groove or notch whereby the arm 69 is releasable for rocking movement to the left or right 115 and thus permits the said arm 71 to engage the rollers 66 and consequently force one of the sets of rollers into the path of the bent arms 46 of the rock shaft (see Fig. 8 of the drawing).

From the above description, taken in connection with the drawings, it will be seen that I have provided for a very positive and practical switch operating mechanism which may be actuated either manually, pneumatically, or by any other suitable power means, 120 whereby a right or left hand trip may be actuated to open or close a track switch as may be desired or necessary. A switch operating mechanism constructed in accordance with my invention, is particularly well 125 130

adapted for its various uses, as stated for the same, on the old style as well as on the new style or types of track switches by reason of the ease and facility with which it 5 may be assembled, installed and operated, and it will be obvious that my invention is adaptable for various changes and modifications in the details of construction and arrangement of the parts thereof, without de- 10 parting from the principles and spirit thereof, or from the scope of the claims appended hereto.

Having shown and described my invention, what I claim as new and desire to set- 15 15 cure by Letters Patent of the U. S. is:—

1. A trip operating mechanism of the class described, in combination with a railway car, comprising a trip engaging member carried by the car for movement to the 20 left or right whereby a selective trip lever positioned outside of the track rails may be actuated, and pneumatic means extending within the car proper for operating said trip engaging member to its operative position. 25

2. A trip operating mechanism of the class described, in combination with a railway car, comprising a horizontally movable trip operating bar supported for movement to 30 opposite sides of a track, and pneumatic means for actuating said bar to the left or right to its engaging operative position.

3. A trip operating mechanism of the class described, in combination with a railway car, comprising a horizontally movable rack bar, the ends of said bar being adapted for movement to a position outside the rails of 35 the track to engage a trip, and pneumatic means for actuating said bar to its engaging 40 operative position.

4. A trip operating mechanism of the class described, in combination with a railway car, comprising a horizontally movable trip operating bar supported for movement to

opposite sides of a track, rollers carried by 45 the respective ends of said bar, and pneumatic means for actuating said bar to bring the rollers into engaging operative position outside the track rails.

5. A trip operating mechanism of the class 50 described, comprising a horizontally movable trip operating bar supported for movement to opposite sides of a track, depending supporting arms at the ends of the trip operating bar, removable, spring retained 55 rollers carried by the supporting arms, and pneumatic means for actuating said bar to bring the rollers into engaging operative position outside the track rails.

6. A trip operating mechanism of the class 60 described, in combination with a railway car, comprising a horizontally movable rack bar, brackets for supporting and guiding said bar, rollers supported by the respective 65 ends of said bar and adapted for movement to a position outside of the track rails, a rack pinion for operating said movable rack bar, and pneumatic means to rotate said pinion to the left or right and actuate said bar. 70

7. A trip operating mechanism of the class described, in combination with a railway car, comprising a horizontally movable rack bar, brackets for supporting and guiding said bar, rollers supported by the respective 75 ends of said bar and adapted for movement to a position outside of the track rails, a rack pinion for operating said movable rack bar, a rotatable spindle and arm connected thereto for rotating said pinion, and pneumatic 80 operating means for actuating said arm whereby the rack bar is moved to its operative, engaged position to either side of the track.

In testimony whereof, I affix my signature 85 hereto.

JAMES P. SKARTCHSEARIS.
